UNITED STATES PATENT OFFICE.

JOHN B. WARING, OF SOUTH MANCHESTER, CONNECTICUT.

MACHINE FOR SORTING THREAD.

Specification of Letters Patent No. 33,117, dated August 20, 1861.

To all whom it may concern:

Be it known that I, JOHN B. WARING, of South Manchester, in the county of Hartford and State of Connecticut, have invented 5 a certain new and Improved Machine for Sizing Silk or other Threads.

My machine is intended to receive a continuous thread not uniform throughout its entire length but larger at some places than 10 at others, and to assort the same, winding the largest upon one bobbin, the smallest upon another bobbin and the medium size upon a third bobbin. This effect has been before produced by machinery but not in 15 the manner in which it is produced by mine.

I hereby declare that the following is a full, clear, and exact description of the novel features of my machine, reference being had to the accompanying drawings and to the 20 characters of reference marked thereon, in which—

Figure 1 is a side elevation of the novel parts, together with the traversing guide used therewith. Fig. 2 is a front view of 25 the same. Figs. 3 and 4 are views of certain parts in different positions showing their operation. Fig. 5 is an outline showing in perspective the traversing guide and bobbin shaft and bobbins. Fig. 6 is a view of the 30 traversing guide as seen from below.

Similar characters of reference indicate like parts in all the figures.

Raw silk and perhaps some varieties of other threads are variable in size in different portions. A continuous thread may be many hundred yards in length with a much greater diameter at one end than at the other, and often with several stages of different sizes intervening between these 40 extremes. It conduces very greatly to the uniformity and perfection of goods produced from such threads, to assort the several sizes placing all the parts which are similar in size upon one bobbin or series of 45 bobbins and all which are of another size upon another series. There are very short lengths of large size thread, in fact mere bunches which cannot be well separated from the remainder of the thread and it is 50 questionable if it would be desirable to effect this result in as much as it would seem to necessitate a dividing of the thread into too many short lengths, but long portions which are large may be very advantageously divided from long portions that are small. Several inventions have been devised at va-

rious times to effect this result, but all such which have come to my knowledge previous to mine have induced a considerable tension on the thread, rendering it liable to break, 60 besides involving several other difficulties more or less serious which mine completely avoids.

To enable others skilled in the art to make and use my invention I will proceed to describe its construction and operation by the aid of the drawings.

In horizontal bearings, attached to the frame work R of suitable winding machines, a spindle or shaft B is delicately poised in 70 such a manner that it is free to rotate to a limited extent. Upon this shaft a lever C, C', is fixed, carrying on one end C a wheel D and on the other end C' a counterbalance W. This counterbalance is capable 75 of delicate adjustment by means of a screw thread on C' as shown so that by turning W around, it is moved outward from B or the reverse. At the point c a bent lever E is hung which carries on its short arm another 80 wheel D'. This bent lever E is so arranged relatively to the other parts as to hold D' in contact with D when the long arm of E is depressed as shown in Fig. 3, but when the long arm of E is elevated as shown in Fig. 4 85 the wheels D and D' are separated by means to be described below. The long arm of E is delicately loaded by the weight e as shown so as to hold D' and D in contact. Upon the long end of E an adjustable cam F is 90 fixed by the screw f. This cam bears upon a stud G mounted on the frame of the machine above B so that as the lever C changes its inclination the adjustable cam F slides upon G. 95

The wheel D is made as true as possible and is free to turn in its bearings on the lever C. The wheel D' is also made as true as possible and is free to turn on its bearings on the short end of the lever E. The thread 100 to be operated on is designated by T. It is contained on a bobbin below, is introduced between the wheels D and D' and is by the action of any suitable mechanism above, moved continuously upward as shown by the 105 arrow. The counterbalance W is adjusted so as to be not sufficient to hold the lever C, C', in a level position but the end C is depressed by its superior gravity or tends to be so depressed. As the thread T moves upward it is gently compressed between the 110 wheels D, D' and although these wheels are

so mounted as to turn very freely there is necessarily some resistance produced to the motion of the thread, thereby tending to move the wheels D, D' in the same direction 5 that the thread is moving. The upward motion of the thread therefore serves as a lifting force to elevate the end C and it is easy to see that with the surfaces of the wheels D, D' held at any given small distance apart the lifting force due to the upward passage of the thread is variable if the size of the thread is variable, becoming greater as the size of the thread is increased and less as it is diminished.

10 The effect of the counter-poise W being constant for any given position in which it may be placed, it follows that the end, C, is elevated by the superior lifting force of the thread, when the thread is large, and is depressed, by reason of insufficiency of the lifting force, when the thread is small. From this motion of the lever C, C' my machine derives the means of determining upon which of the three bobbins the thread 15 shall be wound at any given period, the depression of C causing it, by means which are in common use to be guided upon the bobbin provided for small thread, and the elevation of C causing it by similar means to be guided upon the proper bobbin provided for a larger or the largest threads. This movement is effected and the lever C, C' held for any period in the proper positions without necessitating any appreciable variation 20 in the tension upon the thread, but on the contrary allowing the tension to be almost inappreciable whatever the size of the thread, except when the size of the thread is enlarged very suddenly so that the inertia of the parts becomes of importance.

25 The means by which this is effected as also those by which the lever is made to incline to a greater or less extent with any given change in the size of the thread will now be described.

The working face of the adjustable cam F is curved. It may be so adjusted that as the lever C, C' inclines the center of its curvature coincides with the center of motion of C, C', and as the lever C, C' and its attachments vibrate, and the curved surface slides on the stud G, no effect is produced thereby. This condition is not desirable, but for very delicate sizing it may be very 30 nearly approached. When the cam is so adjusted as to approximate to the position shown in the drawing, the upward motion of C, and the consequent sliding of F upon G, causes the long arm of the lever, E, to be raised and thus separates the wheels D and D' to a greater distance each from the other. Such separation allows the equally easy passage of a larger thread, so that the lever C, C' comes to rest in a new position corresponding to the larger thread which is now

passing through the machine. When a portion of thread comes into the machine which is smaller it acts with too little force to sustain C, C' in its present position, and C, C' accordingly changes its inclination 70 and at the same time causes D and D' to approach until it again finds a position where it feels the same lifting force as at first.

The stud G is mounted eccentrically upon 75 the frame R, at the point represented and is adjustable by a graduated disk g and pointer g' so as to vary its action upon the cam F. A proper guide is attached to E to cause the thread to pass between the wheels 80 D and D'.

The means by which the motion of the wheels, D and D', and lever C, are made to cause a shifting of the thread from one bobbin to another are similar to those used in 85 other machines of this nature, and may be varied under differing circumstances. I will, however, describe the means which I employ for that purpose.

M, M' are two weighted levers. The 90 gravity of the weighted parts of M, M' supports two wires N, N, in contact or nearly in contact with the sliding guide K.

L, L' are two arms attached to the shaft B in such a position that when C is in a 95 horizontal position they come in contact with M, M' and support the weight, thus holding the wires N, N' equally elevated as shown in Fig. 1. As C, C' is inclined from the horizontal position in either direction, 100 suppose for example that shown by Fig. 4, one of the wires, N', is depressed while the other, N, is allowed to rise higher in obedience to the gravity of M, when the traversing guide K is in the proper position. The 105 means by which the elevation and depression of such wires may be made to change the thread from one bobbin to another are well known, but I will briefly describe by the aid of the drawings, one which I find very efficient.

The guide K is so held upon the rod k that any considerable force will cause it to slip and change its position thereon, but when no extraordinary force is exerted it 115 will adhere. The rod k is caused, by the operation of mechanism not represented, to traverse regularly to about the extent proper to distribute the thread upon any one bobbin, or in other words it traverses about the 120 length of a single bobbin. The underside of K is formed in the manner shown in Fig. 6 with rabbets or recesses u, v on its opposite sides which extend for nearly half its length, being a little less than the traverse 125 of K. When the parts are in the position shown in Fig. 1 the ends of the wires N and N' extend into these recesses and just come in contact with the inner ends thereof at each stroke of K. This insures the proper 130

position of K for winding the thread upon the bobbin 2. If now a larger thread passes through the apparatus and raises C into the position shown in Fig. 4 L' turns the lever 5 M' and removes the wire N' from its position in the recess u while at the same time the lever M is released and tends by its weight to elevate N. As soon therefore as the end of K passes N, (which it does from 10 the fact before stated that the recess v was shorter than the throw of K) the latter rises and prevents its return. On the return motion of k, K is shifted thereon and when it has attained its new position it traverses as 15 before but in such a position or in such a path as to wind the thread upon the bobbin 1. If now a portion of thread which is smaller passes through the machine, the reverse action takes place and the guide K is 20 again changed to the bobbin 2 or 3 in accordance with the position of the lever C. Any slight bunches upon the thread not being sufficient to overcome the inertia of the arm C. simply raises the weighted end of E 25 and opens D and D' sufficiently for it to pass without causing any change in the traversing guide.

When it is desired to use the machine for a larger sized thread the stud G is so adjusted as to hold D and D' at a greater distance one from the other with the same position of C. If a greater or less strain is required upon the thread it is regulated by adjusting the counterbalance W upon the 35 arm C' and correspondingly adjusting the weight on the end of E.

When there are very great extremes of size in the thread to be treated, the cam F should be set somewhat as represented in 40 Figs. 3 and 4, so as to change the space between D and D' very greatly by the ordinary motion of C, C'. When all has been assorted or sized the contents of each of the bobbins, 1, 2 and 3, may be again passed 45 through the machine, and each divided into three sizes, and this operation of reassorting or resizing may be repeated several times. This is effected by the adjustment of the

cam F, causing it to be so set, as the refinement of the sizing is increased, that the 50 center of its curved face shall more and more nearly approach to the center B of the lever C, C'. By means of these several adjustments the apparatus may be fitted for 55 all the varying conditions which will present themselves in practice, and it becomes unnecessary to construct a different machine for each class of work.

I do not claim broadly the use in thread assorting machines of all means whereby a 60 transfer of the thread from one bobbin to another may be effected by a greater or less variation in the size of the thread at will, but,

Having now fully described my invention 65 what I claim as new therein and desire to secure by Letters Patent is:

1. Varying the inclination of a lever C by means of slight differences in tension due to variations in the size of a thread running between freely rotating wheels D D' mounted on such lever, without a rubbing friction of the thread against either of such surfaces; and in combination therewith and by means of such changes so produced in the 70 inclination of C increasing and diminishing the distance between the axes of D D'; the whole operating together substantially as herein set forth for the purpose of actuating mechanism which shall induce the shifting 75 of the thread from one bobbin or receiver to another without subjecting the thread to any considerable strain.

2. The construction and arrangement of the continuously revolving thread gripping 85 wheels D D', levers C and E joint e, and surfaces F G, for the purpose herein set forth.

3. The adjustable cam F or its equivalent arranged relatively to the lever E and surface G or their equivalents substantially as herein described.

JOHN B. WARING.
